UNITED STATES PATENT OFFICE.

EZRA S. BUCKNAM, OF PHILADELPHIA, PENNSYLVANIA, ASSIGNOR TO
JOHN A. BRILL, OF PHILADELPHIA, PENNSYLVANIA.

CAR.

No. 801,508.

Specification of Letters Patent.

Patented Oct. 10, 1905.

Application filed January 19, 1905. Serial No. 241,715.

To all whom it may concern:

Be it known that I, EZRA S. BUCKNAM, a citizen of the United States, and a resident of the city and county of Philadelphia, State of Pennsylvania, have invented a new and useful Improvement in Cars, of which the following is a specification.

The object of my invention is to provide a car with removable panels and sashes, so that by shifting them it may be changed from an open to a closed condition, or vice versa. This is accomplished by the peculiar means I employ for shifting the sashes and panels.

It is obvious that while my invention is particularly adapted to car structures it may also be employed wherever sashes or panels may be used.

For a more particular description of my invention reference is to be had to the accompanying drawings, forming a part hereof, in which—

Figure 1 is a perspective of a portion of the interior of a car-wall provided with my improvement. Fig. 2 is a sectional view of a part of the roof structure. Fig. 3 is an enlarged view of a portion of Fig. 2, showing the overlapping part of the sashes. Fig. 4 is a sectional view taken on line 4 4 of Fig. 2 looking in the direction of the arrows. Fig. 5 is a sectional view showing the lower end of a stanchion, a part of a sash of a panel. Fig. 6 is a sectional view on the line 6 6 of Fig. 5 looking in the direction of the arrows. Fig. 7 is an enlarged view showing the manner in which the sash rests on the panel. Figs. 8 and 9 are sectional views showing the sash-locking mechanism. Fig. 10 is a perspective view of the same. Fig. 11 shows the plate which the catch is adapted to engage. Fig. 12 shows a sash-lock, the preferable form being indicated. Fig. 13 is a perspective view of a portion of the guide-tubing. Fig. 14 shows a bolt for the panel. Fig. 15 shows a guide for the panel. Fig. 16 is a sectional view taken on line 16 16 of Fig. 6 looking in the direction of the arrows. Figs. 17 and 18 show modified forms of guides.

Throughout the various views of the drawings similar reference characters designate similar parts.

The car 1 is provided with the usual sills 2, stanchions 3, roof 4, and head-lining 5. The space between the roof 4 and head-lining may be designated as a "sash-pocket," because the

sashes 6 and 7 and panel 8 may be raised and stored therein, as will appear below. If desired, the stanchion 3, sill 2, and roof 4 may be considered as forming a frame in which the sashes and panel are guided.

The sash 6 is suspended from straps or guide-rails 9, which are curved so as to conform to the space in the sash-pocket immediately below the roof, and each of these straps 9 is fixed at its lower end to the inside of the letter-board 10, and at its upper end is secured to the base of the decking 11. The correct outline of one strap is indicated in Fig. 2. Two straps are used for each pocket, and as many sash-pockets are used as there are windows in the car; but as all are identical, a description of more than one is unnecessary. If desired, either more or fewer straps may be used in each sash-pocket, according to the size and weight of the sashes.

The sash 6 is suspended from the strap 9 by means of hangers 12, which are of peculiar construction. Each hanger 12 is provided with a bracket portion 13, which is secured to the upper rail of the sash 6 by screws 14 or other suitable means. Extending upwardly from the bracket 13 are three parallel arms 15, 16, and 17, which are united near their upper ends by a spindle 18. The arms 15 and 16 are also united by means of outwardly-extending lugs 19 and 20, which are connected by a common integral web 21. A roller 22 is mounted on the spindle 18 between the arms 15 and 16, and a second roller 23 is held parallel thereto by a leaf-spring 24, on which it is pivoted, so that the rollers 22 and 23 will always be parallel and the distance between them may vary according to the pressure exerted on the spring. This enables the rollers 22 and 23 to press against and on each side of the strap 9, as shown in Fig. 2, the roller 23 always sustaining the weight of the sash 6.

Between the arms 16 and 17 and pivoted on the spindle 18 is a bell-crank catch 24^a, which has a barb 25 normally pressed outwardly by a leaf-spring 26, as shown in Fig. 9. The end 27 of the bell-crank lever 24^a is curved and placed so as to normally rest a little below the plane of the web 21. The barb 25 engages a catch-plate 28, which is fixed flush with the surface of the letter-board 10 and immediately above a small recess 29. The manner in which the catch 24^a releases the plate 28 will appear below.

At each side of the sash 6 are parallel guides 30, which have inturned flanges 31, which run at a slight angle to the plane of the sash and extend the entire length of each side. The lower sash 7 has grooves 32, which take the flanges 31 and thereby guide the sash 7 in the lower portion of its movements to and including the time it engages the web 21. Just before the sash 7 engages the web 21 it engages the end 27 of the bell-crank catch 24^a and acts against the pressure of the spring 26 to release the barb 25 from the plate 28. This obviates any danger of a premature raising of the sash 6, which might occur if these catches 24^a were omitted and the flanges 31 stuck in the grooves 32. The upper ends of the sash 7 are provided with wedge-plates 33, which engage the tubing 34 and force the sashes together to form a tight joint when in the position shown in Fig. 2, and when the lower sash 7 is raised the guides 31 carry its upper end a little away from the surface of the sash 6 because of their divergence therefrom.

The sash 7 is secured by means of a suitable lock 35, the bolt of which may enter suitable recesses 35^a.

The guide or tubing 34 may be either four-sided, as shown in Fig. 13, or three-sided, as shown in Fig. 4. The latter form is preferred because of its lightness and cheapness. In either case this tubing 34 is made in three parts 36, 37, and 38, and each may be provided with notches or recesses 39, adapted to receive a bolt on the panel 8. The tubing 34 extends from the decking 11 to the floor 2 and is curved so as to conform to the stanchion 2, as shown on Figs. 2 and 5. The tubing 34 is preferably made of metal. If desired, a solid bar 34^a may be used in lieu of the tubing 34, as shown in Fig. 17, or the three-sided tubing may be reversed, as shown in Fig. 18.

The panel 8 comprises two sheets 40 and 41, which are united by strips 42 and 43 at the top and bottom, respectively, and by intermediate strips 44. Guides 45 are also interposed, as shown in Fig. 15. These guides 45 are fixed to one sheet and have a pin-and-slot connection with the other, so as not to interfere in any way with the flexibility of the panel. The strip 42 is slightly enlarged outwardly, so as to receive and support the sash 7 and form a tight joint therewith.

The strips between the sheets 40 and 41 terminate a little short of the edges of the sheets 55 which straddle the tubular guide 34, one on each side. These sheets fit snug against the sides of the guide 34, because the thickness of the separating-slats is such that this result is secured. As these slats are preferably made of wood, they are not suitable for guiding the panel, so that I provide the metal guides 45 above, which are so positioned as to engage the only exposed face of the guide 34 which is not engaged by the sheets 40 and 41.

If the guide 34 is reversed, as shown in Fig.

18, the panel 8 may slide inside instead of outside of the flanges.

The panel 8 is held in its various positions by means of the spring-actuated bolts 46, which may be operated by bringing their handles 47 together against the action of the springs 48, which press against the heads 49 and shoulders 50, which are fixed to one of the flexible sheets. By so doing the bolts 46 are withdrawn from the notches 39 and may be returned thereto under the action of the springs 48 by merely releasing the handles 47.

From the foregoing the operation of the device will be readily understood. Assuming the parts to be in the positions indicated in Figs. 2 and 5, the lower sash 7 is raised in the usual manner, and its upper end is guided by the flanges 31 in the grooves 32. At the upper limit of its independent movement it releases the catch 24 and engages the projecting web 21, when both sashes move up together, guided by the strap 9 and hangers 12. They are locked by bolt 35 entering one of the recesses 35^a in the stanchion 2. If the car is to be converted from a closed to an open condition, the sashes 6 and 7 should be raised to the position indicated by dotted lines in Fig. 2. The panel 8 is then raised by releasing the bolts 46 and shoved to the position which is also indicated by dotted lines in Fig. 2. When in place, the handles 47 are released and the bolts 46 engage the walls of the notches 39. A reversal of the above-mentioned steps will lower the panel and sashes to their initial position.

Many other embodiments of my invention might be shown, as it is applicable to many kinds of structures as well as different type of cars or certain features may be employed without others. I therefore do not regard my invention as limited to the precise structure shown and described, but regard it as broad enough to cover all structures that come within the scope of the claims.

Having thus described my invention, what I claim is—

1. In a device of the class described, a frame, an upper sash, a lower sash adapted to be raised abreast of the upper sash and a catch so situated as to be released when the lower sash is moved abreast of the upper sash and not before.

2. In a device of the class described, a frame, a sash suspended in said frame, a catch, spring-controlled and pivotally mounted on said sash, guides on said sash and a second sash whose movement is determined by said guides and which is adapted to release said catch.

3. In a device of the class described, a frame, a sash suspended in said frame, guides on said sash, spring-controlled bell-crank catches pivoted near the top of said sash, and a lower sash whose movement is determined by said suspended sash and which is adapted to engage and release said bell-crank catches.

4. In a device of the class described, a frame, a sash suspended in said frame with guides secured thereto, said guides being parallel and each provided with a flange that slightly diverges from the plane of the sash, catches pivoted to the upper edge of said sash, a second sash which is adapted to be guided in its movement by said guides and to so move that it operates and controls said catches.
- 10 5. In a device of the class described, a pair of stanchions, a tubular guide secured to each of said stanchions and a flexible panel having parts straddling each of said tubular guides.
- 15 6. In a device of the class described, a pair of stanchions, a projecting guide secured to each of said stanchions, and a flexible panel having parts straddling each of said projecting guides.

7. In a device of the class described, a pair of stanchions, a projecting and notched guide secured to each of said stanchions, a flexible panel having parts straddling each of said guides, and spring-controlled bolts in said panel which are adapted to engage the notches in the guides.

20 8. As an article of manufacture, a panel composed of parallel sheets, crossings between and uniting said sheets, and guides fixed to one of said sheets and slidably connected to the other.

25 Signed this 10th day of January, 1905.
